O. N. Hubbard,

UNITED STATES PATENT OFFICE.

JOHN M. JOY, OF WATERBURY, CONNECTICUT.

DESIGN FOR A BANNER.

SPECIFICATION forming part of Design No. 21,927, dated October 25, 1892.

Application filed August 1, 1892. Serial No. 441,879. Term of patent 3½ years.

To all whom it may concern:

Be it known that I, JOHN M. JOY, a citizen of the United States, residing at Waterbury, in the county of New Haven and State of Connecticut, have invented and produced a certain new and original Design for a Banner, of which the following is a full, true, and exact specification.

Reference is to be had to the accompanying drawing, forming a part thereof.

The leading features of my design comprise the central figure of a stag, having above it the figure of the flying eagle, bearing a scroll, and beneath it a wreath, upon either side of which latter are represented partially-furled United States flags. Minor features consist of the six figures of the flying cupid at the upper and lower corners and upon either side of the wreath.

In the drawing, 1 denotes the central representation of the stag, and 2 mountains in the background.

3 is the figure of the eagle above the stag and bearing a scroll 4.

The wreath below the figure of the stag is denoted by 5, and the flags by the numeral 6.

At the top of the design is a ribbon-scroll 7.

I claim—

The design for a banner, substantially as shown and described.

In testimony whereof I affix my signature in presence of two witnesses.

JOHN M. JOY.

Witnesses:

WILSON H. PIERCE,
J. S. RYMILL.
